PROCESS FOR HUMIDIFYING FINISHER LAPS OF COTTON.

Application filed March 6, 1926. Serial No. 82,960.

Our invention relates to a new and improved process for humidifying cotton laps and particularly finisher cotton laps.

In the spinning of cotton, usually the 5 ton leaves the picker room practically bone dry and thus is short about eight percent of the moisture which the fiber requires for its proper strength and treatment. Various means have been employed to restore the 10 humidity to the cotton and in the present general practice the humidification of the carding room and spinning room has been relied upon to restore the proper moisture content in the cotton fiber. It has also been 15 suggested, though so far as we are aware it has not been practiced, to spray the raw cotton when it is first rolled into sheets or laps. The objection to the latter process is that the cotton sheet or lap after being 20 sprayed must be subjected to a number of treatments before it leaves the finisher picker, and in these treatments this added moisture is largely lost so that the actual moisture content of the cotton fiber in the 25 finisher lap cannot be accurately controlled. Moreover, where the moisture is applied to the cotton during the preliminary picking treatment, if sufficient moisture is introduced to leave the finisher lap with eight 30 percent of moisture, it will be found that there is too much moisture in the cotton for its proper treatment and effective cleaning in the breaker and intermediate pickers.

In order that the problem of properly and 35 accurately humidifying the finisher laps may be solved, we have conceived the idea of withholding the spraying of the fiber until it reaches the finisher picker and we thus apply the moisture by spraying at a 40 point where treatment of the lap in an unhumidified atmosphere has been completed and it will be noted that the sprayed lap as it leaves the finisher picker goes directly to the carding room where the humidified 45 atmosphere will prevent further loss of moisture from the cotton laps. Hence, it follows that an accurate and correct amount of moisture can be added to the laps at the finisher picker and that the moistened cotton 50 can be made to retain this amount of added moisture due to the fact that it re-

ceives no further treatment in unhumidified atmosphere.

As illustrative of an apparatus capable of carrying out our above process, we show 55 in the drawings in side elevation a finisher picker comprising a lap apron frame 1 having stop bearings 2 to receive the pins of the several laps 3, 4, 5 and 6 which are to be fed by means of the apron 7 to a beater 60 8 whence the treated fiber passes between the screens in a screen chamber 9 which discharges the cotton in a layer 10 that passes through suitable calendar rolls 11 and is wound into the finisher lap 12. The laps 3, 65 4, 5 and 6 from which the cotton layers are supplied to the apron usually come to the finisher picker from an intermediate picker, the laps having been first treated on a breaker 70 picker.

We arrange an atomizer spray 13 to which air and water are supplied respectively by the pipes 14 and 15 and which will operate, in the manner well understood in this art, to direct a spray both on the layer 10 and 75 on the lap 12 thus applying moisture to both sides of the lap layers as wound into the lap, and the finisher lap, as thus humidified, is transported directly to the carding room where the humidification of the atmosphere will prevent the evaporation of 80 the moisture introduced into the lap by the spray.

Our invention can of course be carried out by other means of introducing moisture than 85 the spray shown, and it is contemplated that any practical and convenient means for moistening the layer of cotton that is wound into the finisher lap at the finisher picker may be employed.

Having thus described our invention, what we claim as new and desire to secure by Letters Patent, is:—

1. The herein-described process for humidifying cotton laps, which consists in introducing into the cotton layer as discharged from the finisher picker requisite moisture to restore its natural moisture content. 95

2. The herein-described process of humidifying cotton laps, which consists in spraying on the cotton layer as it is rolled into the finisher lap the requisite amount of 100

moisture to substantially restore its natural moisture content.

3. The herein-described process of humidifying cotton laps for spinning, which consists in spraying on the cotton layer as it is rolled into the finisher lap the requisite amount of moisture to substantially restore its natural moisture content, and then trans-

ferring the moistened finisher lap without further treatment directly into the humidified atmosphere of the carding room. 10

In testimony whereof we affix our signatures.

JAMES L. BYERS.
